RAILWAY TRAFFIC CONTROLLING
APPARATUS

Paul H. Crago, Wilkinsburg, and Arthur E. Dodd,
Swissvale, Pa., assignors to The Union Switch &
Signal Company, Swissvale, Pa., a corporation
of Pennsylvania

Application April 24, 1935, Serial No. 17,978

11 Claims. (Cl. 246—221)

Our invention relates to railway traffic controlling apparatus, and has for an object the provision of apparatus controlled by a car for causing operation of a traffic controlling device 5 when a car passes over a given track section in less than a predetermined time interval.

We will describe two forms of apparatus embodying our invention, and will then point out the novel features thereof in claims.

10 In the accompanying drawing, Fig. 1 is a diagrammatic view illustrating one form of apparatus embodying our invention. Fig. 2 is a diagrammatic view illustrating a modification of a portion of Fig. 1, and also embodying our invention.

Similar reference characters refer to similar parts in each of the two views.

Referring first to Fig. 1, the reference characters 2 and 3 designate the rails of a stretch 20 of railway track designated by the reference character X. The rails of track X are divided into three relatively short track sections 1T, 2T and 3T by means of insulated joints 4. A traffic controlling device, here shown as a switch, is located in section 3T and is designated by the reference character 5. Each track section is provided with the usual track circuit including a battery 6 connected across the rails at one end of the section and a track relay designated by 30 the reference character R with a distinguishing prefix connected across the rails at the other end of the section.

The reference characters B and C designate the positive and negative terminals, respectively, 35 of a source of current not shown in the drawing.

Associated with relay 1TR is a time measuring mechanism, here shown as two slow pick-up slow-release relays and designated by the reference characters 1TP and A1TP. The relay 1TP 40 is normally energized and is controlled over a front contact 7 of relay 1TR. The relay 1TP, therefore, will be energized or deenergized depending upon the condition of relay 1TR. The relay A1TP is normally deenergized and is controlled over a back contact 8 of the relay 1TP. The relay A1TP, therefore, will be energized when the relay 1TP is in its deenergized condition and will be deenergized when the relay 1TP is in its energized condition. The manner in which 45 relays 1TP and A1TP function for timing purposes will be explained more in detail hereinafter.

It will be noted that the track relay 1TR is normally energized over a stick circuit which includes its own front contact 9. The pick-up circuit for the relay 1TR extends from rail 2 over

wire 10 to a front contact 11 of relay A1TP and thence over wire 12 and the winding of relay 1TR to the opposite rail 3. The relay 1TR, therefore, may be deenergized when section 1T becomes occupied but may be energized when section 1T is unoccupied only if relay A1TP is in its energized condition. The relay 1TR is controlled in this manner to prevent the possibility of relay 1TR becoming momentarily picked up should the distance between trucks on a car 10 be sufficient to bridge section 1T. That is, the release time of relay 1TP added to the pick-up time of relay A1TP holds the pick-up circuit for relay 1TR open for a predetermined length of time which will usually be sufficient to maintain 15 relay 1TR in its deenergized condition during the time the front and rear trucks of a long car may be bridging the section 1T. As will be explained more in detail hereinafter, the release time of relay 1TP combined with the pick-up 20 time of relay A1TP is also employed for timing the speed of cars traversing section 1T. The pick-up time of relay 1TP added to the release time of relay A1TP maintains the pick-up circuit for relay 1TR closed momentarily over front contact 11 of relay A1TP, so that when section 1T is vacated, relay 1TR may attain its energized condition and reclose its stick circuit before its pick-up circuit becomes opened.

The reference character MR designates a locking relay which, as will be explained hereinafter, is effective at times to prevent operation of the switch by the second truck of a car. The relay MR is provided with a pick-up circuit which passes from terminal B through front contact 13 35 of relay 1TR, back contact 14 of relay 2TR and relay MR to terminal C, and with a stick circuit which passes from terminal B through front contact 15 of relay 3TR, front contact 16 of relay MR and relay MR to terminal C. The relay MR, 40 therefore, will be picked up when relay 1TR is in its normal energized condition provided that relay 2TR is in its deenergized condition, and will be maintained in such condition until relay 3TR is released.

The reference character WR designates a switch control relay which is normally deenergized. The relay WR is provided with a pick-up circuit and a stick circuit. The pick-up circuit passes from terminal B through back contact 17 50 of relay 1TR, back contact 18 of relay 2TR, back contact 19 of relay A1TP, back contact 20 of relay MR, wire 31, and relay WR to terminal C. The stick circuit passes from terminal B through front contact 21 of relay 3TR, front contact 22 55

of relay WR and relay WR to terminal C. The relay WR, therefore, will be picked up when relays 1TR and 2TR both become deenergized provided relays A!TP and relay MR are both in their normal deenergized condition and will be maintained in such condition until relay 3TR is released.

As indicated by a dotted line, a motor M is operatively connected with the switch 5 through the medium of a standard switch machine (not shown) to operate the switch to a normal position for directing a car to the track designated by the reference character 10A, or to operate the switch to a reverse position for directing a car to the track 10B. The operation of the motor M is governed by the switch control relay WR in a customary manner. With relay WR deenergized, the motor is provided with a circuit passing from the terminal B over front contact 23 of the track relay 3TR, back point of contact 24 of relay MR, controller contact 25-26 operated by the motor and closed except when the switch 5 is moved to the full normal position, armature 27, back point of contact 28 of relay WR, and motor field winding 29 to the terminal C. When relay WR is energized over its pick-up circuit hereinbefore described, current flows from the terminal B over front contact 23 of relay 3TR, front point of contact 24 of relay WR, armature 27, controller contact 25-30 operated by the motor and closed except when the switch 5 is moved to the full reverse position, front point of contact 28 of relay WR, and motor field winding 29 to the terminal C. The flow of current in armature 27 when relay WR is energized is such as to cause the motor M to rotate in a direction for operating the switch 5 to its reverse position, whereas the flow of current in armature 27 when relay WR is deenergized is such as to cause the motor M to rotate in a direction for operating the switch 5 to its normal position. It follows that with relay WR deenergized the switch 5 is set to direct a car to the track 10A, and with relay WR picked up the switch is set to direct a car to the track 10B.

A car entering the track section 1T will release the track relay 1TR which will in turn deenergize relay A!TP. At the expiration of a given interval of time relay A!TP will become released, thus energizing relay A!TP. At the expiration of another given time interval, relay A!TP will become picked up. If the speed of the car is slow enough so that relay A!TP reaches its energized position before the car enters section 2T and releases relay 2TR, then the pick-up circuit for relay WR will become opened by the opening of back contact 19 of relay A!TP and relay WR will remain deenergized. Under this condition, the switch 5 will not be moved and the car will advance over the switch to track 10A. If the speed of the car is high so that it traverses the section 1T and enters section 2T before relay A!TP becomes picked up, the switch control relay WR will become energized as soon as the car enters section 2T and shunts relay 2TR, the pick-up circuit for relay WR being closed over the back contacts 17 and 18 of relays 1TR and 2TR, respectively. Under this condition, the motor M will be operated to move the switch 5 to its reverse position and the car will advance over the switch to the track 10B. As the car passes from the section 2T into the section 3T, the shunting of track relay 3TR will open the front contact 23 in the motor operating circuit so that the switch 5 may not be operated with a car in section 3T even when relay WR returns to its normal deenergized condition due to the opening of its stick circuit by the open-

ing of front contact 21 of relay 3TR. When the car vacates section 3T, the relay 3T will become energized so that the operating circuit for motor M will become closed by the closing of front contact 23 of relay 3TR. Thus, the motor M will be caused to operate the switch to its normal position. To sum up the operation of the apparatus illustrated in Fig. 1, a car traveling through section 1T above a predetermined speed will cause switch 5 to be automatically set in a position to advance the car into track 10B, whereas a car moving below such given speed will cause switch 5 to remain in its normal position so that the car will advance into track 10A. At such times as the switch has been reversed to direct the car into the track 10B, the vacating of section 3T will cause the automatic restoration of switch 5 to its normal position.

It will be noted that the timing of the car in section 1T is accomplished by the utilization of the release time of relay 1TP and the pick-up time of relay A!TP. That is, the time required for relay 1TP to become released added to the time required for relay A!TP to become picked up is used for determining whether the car is traveling above or below a predetermined speed. We have found that the total operating time of two such relays is substantially constant regardless of changes in temperature, and also regardless of changes in battery voltage through the usual range of battery voltage variation. For example, even though an increase in temperature may bring about a corresponding decrease in the release time of relay 1TP, this increase in temperature will also cause a corresponding increase in the pick-up time of relay A!TP so that the combined operating time of the two relays remains substantially constant. Our invention, therefore, provides a simple and reliable timing means for determining the speed of a car, which means is substantially constant regardless of changes in temperature and battery voltage.

It will be noted that the locking relay MR will be energized when relay 1TR becomes energized and relay 2TR becomes deenergized in response to the car departing from section 1T and entering section 2T, and that relay MR will be stuck up as long as section 3T is unoccupied. It will also be noted that when relay MR is energized the pick-up circuit for relay WR becomes opened so that with the relay MR energized relay WR may not be energized. The locking relay MR thus prevents the possibility of the switch being caused to move by the second set of trucks of a slow moving car entering section 1T if the spacing between the trucks of such car is of sufficient length to bridge section 1T. In other words, if relay MR were not provided, there is a possibility that if relay 1TR should become energized while the front and rear trucks of a slow moving car were bridging section 1T, the pick-up circuit for relay WR may become closed by the releasing of relay A!TP. Under this condition, when the rear set of trucks of such a car enters section 1T, the pick-up circuit for relay WR may become closed over back contacts 17, 18 and 19 of relays 1TR, 2TR and A!TP, respectively. Since, however, back contact 20 of relay MR is also included in the pick-up circuit for relay WR, this pick-up circuit cannot be closed as long as relay MR is energized, which relay will remain energized until the car enters section 3T.

Many applications for the apparatus of Fig. 1 will naturally suggest themselves to those skilled in the art. For example, at hump or scale tracks,

5 a car moving on the scale track X at too high a speed to permit weighing and classification of the car will automatically cause switch 5 to be reversed to direct that car to an emergency track 10B where it can be later brought back and again pushed over the scales. Cars moving over the scales slow enough to be properly weighed and classified will pass over the switch 5 in its normal position and move to the usual classification yard 10 (track 10A).

Referring now to Fig. 2, the reference character PB designates a manual device, here shown as a push button, for causing the switch control relay WR to return to its normal deenergized condition after a car has moved over the switch. The push button PB is provided with a normally closed contact 32 which may be substituted for front contact 21 of relay 3TR in the stick circuit for relay WR. The pick-up circuit for relay WR connects to wire 31 in a manner similar to that just described for the apparatus shown in Fig. 1. Likewise, all other apparatus operates in conjunction with the push button PB in a manner similar to that described for the apparatus illustrated in Fig. 1.

It is readily apparent that the push button PB provides a means for manually opening the stick circuit for relay WR. Relay WR, therefore, may be controlled by an attendant at the switch so that switch 5 may be caused to return to its normal position or to remain in its reverse position after having been caused to assume such position by a passing car.

35 Although we have herein shown and described only two forms of apparatus embodying our invention, it is understood that various changes and modifications may be made therein within the scope of the appended claims without departing from the spirit and scope of our invention.

40 Having thus described our invention, what we claim is:

1. In combination, a stretch of railway track including a railway traffic controlling device having a first and a second position and normally occupying the first position, operating means for moving said device, a slow release relay having an initial condition and an operated condition, a slow pick-up relay having an initial condition and an operated condition, means effective to initiate the operation of said slow release relay when a particular section is occupied by a car approaching said device, means effective to initiate the operation of said slow pick-up relay when said slow release relay has completed its operation, control means governed by the slow pick-up relay and effective to cause the operating means to move the device to its second position if and only if said slow pick-up relay is in its initial condition when the car enters another particular section, and means governed by the car after having passed the device to control the operating means to automatically move the device back to its first position.

2. In combination, a stretch of railway track including a railway traffic controlling device having a first and a second position and normally occupying the first position, operating means for moving said device, a slow release relay having an initial condition and an operated condition, a slow pick-up relay having an initial condition and an operated condition, means effective to initiate the operation of said slow release relay when a particular section is occupied by a car approaching said device, means effective to initiate the operation of said slow pick-up relay when

said slow release relay has completed its operation, control means governed by the slow pick-up relay and effective to cause the operating means to move the device to its second position if and only if said slow pick-up relay is in its initial condition when the car enters another particular section, and manually controlled means for causing the operating means to move the device back to its first position after the car has passed over the device.

3. In combination, a stretch of railway track including a railway switch having a first and a second position and normally occupying the first position, operating means for moving the switch, a first track section traveled by a car in approaching the switch, a slow release relay having an initial condition and an operated condition, a slow pick-up relay having an initial condition and an operated condition, means effective to initiate the operation of said slow release relay when said section is occupied by the car, means effective to initiate the operation of said slow pick-up relay when said slow release relay has completed its operation, a second section between said first section and said switch, a track circuit for said second section including a track relay, and control means governed jointly by said slow pick-up relay and said track relay for automatically causing said operating means to move the switch to the second position if the car enters said second section before said slow pick-up relay has completed its operation.

4. In combination, a railway switch, operating means for moving the switch, a first and a second track section traversed by a car in approaching the switch, a slow pick-up relay having an initial condition and an operated condition, means for initiating the operation of said slow pick-up relay a predetermined time interval after the car enters said first section, and control means effective to cause the operating means to move the switch if said relay has not completed its operation when the car enters said second track section but ineffective to control the operating means if said relay has completed its operation when the car enters said second track section. 45

5. In combination, a railway switch having a first and a second position and normally occupying its first position, operating means for moving the switch, a first and a second track section traversed by a car in approaching the switch, a first and second track relay one for each section, a normally energized slow-release relay deenergized when said first track relay is released, a normally deenergized slow pick-up relay energized when said slow-release relay is deenergized, control means governed by said first and second track relays and by said slow pick-up relay and effective at times to control the operating means to move the switch to the second position, and other track circuit means responsive to a car moving over said switch for causing said control means to become effective to cause said operating means to move said switch back to its first position when the car has passed beyond said switch

locking relay including a front contact of the track relay for the first section and a back contact of the track relay for the second section, and a stick circuit for said locking relay including a 5 front contact of the track relay for the third section.

7. In combination, a first and a second and a third track section to be successively traversed by a car, a track relay for each section, a normally 10 energized slow release relay deenergized when the track relay for the first section is released, a normally deenergized slow pick-up relay energized when said slow release relay is deenergized, a switch in the third section, a switch control 15 relay for governing said switch, a pick-up circuit for said switch control relay including a back contact of the track relay for the first section as well as a back contact for the track relay for the second section and a back contact of the slow pick-up relay, and a stick circuit for said switch control relay including a front contact of the track relay for the third section.

8. In combination, a stretch of track including a first and a second section to be successively traversed by a car, a stick relay for the first section, a track relay for the second section, one slow pick-up slow release relay normally energized but deenergized when said stick relay is released, another slow pick-up slow release relay normally 30 deenergized but energized when said one slow pick-up slow release relay is deenergized, a pick-up circuit for said stick relay including the rails of said first section and a front contact of said other slow pick-up slow release relay, a stick circuit 35 for said stick relay including its own front contact and the rails of said first section, a railway switch in said stretch, and means for operating said switch governed in part by said other slow pick-up slow release relay and by the track 40 relay for the second section.

9. In combination, a slow release relay normally energized, a slow pick-up relay normally deenergized, a circuit for said slow pick-up relay controlled by a back contact of said slow release 45 relay, a railway traffic controlling device, oper-

ating means for moving said device, means for deenergizing said slow release relay when a car approaching said device occupies a given section, and control means governed by the slow pick-up relay effective to cause said operating means to move said device if the car traverses such given section in less than a measured time interval. 5

10. In combination, a timing mechanism including two slow acting relays one relay of which is set into operation when the other relay completes its operation, a railway traffic controlling device having a first and a second position and normally occupying the first position, operating means for moving said device, means for initiating the operation of said other slow acting relay when a car approaching said device occupies a given section, and control means governed by said one slow acting relay for causing the operating means to move the device to the second position or to retain the device in the first position depending 15 upon the condition of said one slow acting relay when the car enters the next successive section. 20

11. In combination, a railway switch having a first and a second position, operating means for moving the switch, a normally deenergized switch 25 controlling relay, circuit means controlled by said relay and effective when the relay is deenergized to cause the operating means to move the switch to the first position and effective when the relay is energized to cause the operating means to move the switch to the second position, a first track circuit responsive to a car approaching the switch and effective at times to energize said relay for automatically causing the switch to be moved to 30 the second position, a second track circuit responsive to a car passing over the switch, a stick circuit for said relay controlled by said second track circuit, and other track circuit means responsive to a car moving away from said switch 35 for opening the stick circuit to deenergize said relay and automatically restore the switch to the first position. 40

PAUL H. CRAGO.

ARTHUR E. DODD. 45
